UNITED STATES PATENT OFFICE

MERVYN S. MACK, OF NEW YORK, N. Y.

CIGARETTE-HOLDER.

1,263,263.

Specification of Letters Patent. Patented Apr. 16, 1918.

Application filed March 5, 1918 Serial No. 220,481

To all whom it may concern:

Be it known that I, MERVYN S. MACK, a citizen of the United States, and a resident of the city of New York, borough of Manhattan, in the county and State of New York, have invented a new and Improved Cigarette-Holder, of which the following is a full, clear, and exact description.

My invention relates to cigarette holders characterized by the provision of means for automatically ejecting cigarettes from the holder.

An object of the invention is to provide a simple, inexpensive and attractive cigarette holder.

I attain the above and other objects of my invention by the structure conventionally disclosed in the accompanying drawings, wherein similar characters of reference indicate corresponding parts in all the views.

Figure 1 is a longitudinal section through my cigarette holder in operative position;

Fig. 2 is a similar section showing the holder in the normal or inoperative position after a cigarette butt has been ejected therefrom;

Fig. 3 is a longitudinal section through a cigarette holder which is of circular cross section, as distinguished from oval shown in Figs. 1 and 2;

Fig. 4 is a cross section on line 4—4, Fig. 3; and

Fig. 5 is a cross section through an oval cigarette holder illustrating a modified construction of the stop for the plunger.

Referring to the drawings, 6 is the shell or housing, which is preferably slightly flared at one end to receive a cigarette 7. The other end of the shell receives the mouthpiece 8. The shell may be of circular cross section, as shown in Fig. 3, or oval as shown in Figs. 1, 2 and 5. A tubular plunger 9 is mounted to slide in the housing 7. This plunger is of oval cross section if it fits an oval shell, and of circular cross section if it fits a circular shell. The plunger 9 has an apertured end wall 10 at the front end which is to be in contact with the cigarette 7 when the same is fitted therein. This end wall forms an abutment for one end of a spring 11, the other end of which abuts against an apertured wall 12 located in proximity to the mouthpiece end within the shell or housing 7.

When the shell is circular, as in Figs. 3 and 4, then the end of the mouthpiece can

be threaded into the shell (see Fig. 3), and against this end the other end of the spring may abut. The tubular plunger 9 is of a smaller size than the shell, to provide a clearance between the two to accommodate a flat spring 13 secured to the plunger. The rear end of the plunger carries a collar 14 sufficiently wide to properly guide the plunger within the shell without causing the front end to bind during the movement of said plunger under the action of the spring 11.

The shell has a cut-out or opening 15 into which the free end of the spring 13 is adapted to enter when the plunger is restricted by means of a cigarette, as shown in Figs. 1 and 3. This opening is covered by a shield 16 of any suitable shape. This shield carries a button 17 and a housing 18 for said button. This button surmounts the end of the spring 13 when the same is in the cut-out 15, and by pressing on said button the spring 13 is disengaged from the shell and, therefore, the spring 11 allowed to force the plunger forwardly, thereby ejecting a cigarette, as shown in Fig. 2.

The movement of the plunger under the action of the spring 11 is limited by a stop 19 in the shape of a pin or pins carried by the shield 16 and extending into the shell through openings formed in the shell or the cut-out 15 if the same is wide enough. These pins will be in the path of the collar 14 and, therefore, arrest the movement of said plunger when the collar strikes the pins (see Figs. 2 and 4).

In case of a circular shell, as shown in Figs. 3 and 4, the stops or pins 19 are disposed to each side of the flat spring 13; in which case these pins, in addition to forming stops, serve as a guide for the plunger and prevent the turning of same and, therefore, maintain the flat spring in alinement with the opening 15.

In case of the oval shells, as shown in Figs. 1, 2 and 4, the pins will serve as a stop only; in which case the stop may be formed in the bottom of the shell, as shown in Fig. 5. Then there will be two shields on the shell 7.

When a cigarette is placed into the cigarette holder the tubular plunger is forced to retract. In consequence, the free end of the flat spring 13 is brought into the cut-out 15. The entrance of the end of the flat spring into the cut-out raises the button 17

to the operative position and the resistance of the coil spring 11 maintains the end of the spring in engagement with the cut-out until the flat spring 13 is depressed by the 5 button 17, as previously described.

I claim:

1. A cigarette holder comprising a tubular housing adapted to receive a cigarette at one end, a mouthpiece at the other end of 10 the housing, a tubular plunger having a collar at the rear end fitting snugly into the housing, a coil spring within the housing for moving the plunger toward the end for receiving the cigarette, a spring on the 15 plunger, said housing having a cut-out adapted to be engaged by the spring to render the coil spring inoperative, a button on the housing in register with the cut-out for disengaging the spring from the recess, 20 and a stop associated with the housing and lying in the path of the collar, whereby the movement of said plunger under the action of the coil spring is limited.

2. A cigarette holder comprising a tubular 25 housing adapted to receive a cigarette at one end, a mouthpiece at the other end of the housing, a plunger having an outer collar fitting snugly into the housing, a coil spring for moving the plunger toward the end for receiving the cigarette, a spring on the 30 plunger, said housing having a cut-out to be engaged by the spring to render the coil spring inoperative, a shield covering the cut-out of the housing, a button on the shield registering with the cut-out, and a stop carried by the shield projecting through the housing into the path of the 35

plunger's collar to limit the movement of the plunger under the action of the coil 40 spring.

3. A cigarette holder comprising a tubular housing adapted to receive a cigarette at one end, a mouthpiece at the other end of the housing, a plunger having a collar fitting snugly into the housing, a coil spring for 45 moving the plunger toward the end for receiving the cigarette, a spring on the plunger, said housing having a cut-out adapted to be engaged by the spring to render the coil spring inoperative, a shield covering 50 the cut-out of the housing, a button on the shield registering with the cut-out, and pins carried by the shield and projecting through the housing into the path of the plunger's collar to limit the movement of 55 the plunger, said pins being disposed to each side of the spring on the plunger.

4. A cigarette holder comprising a tubular housing adapted to receive a cigarette at one end, a mouthpiece at the other end of 60 the housing, a plunger having a collar at the rear end fitting snugly into the housing, a coil spring for moving the plunger toward the end for receiving the cigarette, a spring 65 on the plunger, said housing having a cut-out adapted to be engaged by the spring to render the coil spring inoperative, a shield covering the cut-out, a button on the shield registering with the cut-out, and a stop for 70 the plunger carried by the shield, said stop also serving as a guide for the plunger to maintain the spring on the plunger in alignment with the cut-out.

MERVYN S. MACK.
